UNITED STATES PATENT OFFICE.

HENRY H. JACOBS, OF WASHINGTON, DISTRICT OF COLUMBIA.

DESIGN FOR A SPOON.

SPECIFICATION forming part of Design No. 20,822, dated June 9, 1891.

Application filed May 12, 1891. Serial No. 392,500. Term of patent 3½ years.

To all whom it may concern:

Be it known that I, HENRY H. JACOBS, a citizen of the United States, residing at the city of Washington, in the District of Columbia, have invented and produced a new and original Design for Spoons, of which the following is a specification, reference being had to the accompanying drawings, forming part thereof.

10 The leading feature of my design consists of the following elements displayed and arranged as illustrated: The handle consists of the representation of a cannon finished at its end with a cap-piece, the top of which is 15 decorated with a rosette of leaves radiating from a central point, from which extends an ornamental knob *a*. Extending downwardly from the cap-piece and encircling the end of the cannon is a border of leaves. The can-

non is ornamented with a floral wreath *c*, entwining it lengthwise. The cannon is divided into two sections by a beaded ring, under which appear the numerals "1861." Upon the upper section of the cannon is a perspective view of the Mount Vernon Mansion. 25 Upon the lower section is a perspective view of the Arlington Mansion. Within the bowl of the spoon is a landscape view showing the United States Capitol, and in the foreground the statue erected to the memory of President 30 Garfield.

What I claim is—

A design for a historical spoon, as herein described and illustrated.

HENRY H. JACOBS.
